SAFETY DEPOSIT RECEPTACLE

Filed April 9, 1928

FIG. 1

FIG. 2

FIG. 3

FIG. 4

FIG. 5

INVENTOR
EDWARD S. PEER
BY Munn & Co.
ATTORNEY

FIG. 6

UNITED STATES PATENT OFFICE.

EDWARD S. PEER, OF LOS ANGELES, CALIFORNIA.

SAFETY DEPOSIT RECEPTACLE.

Application filed April 9, 1928. Serial No. 268,741.

My invention relates to safety deposit receptacles of the character embodied in my United States Patent, No. 1,634,884, issued July 5, 1927, by which one is able to protect one's valuables against theft, particularly when traveling in a train or other public conveyance.

It is a purpose of my present invention to provide in a safety deposit receptacle 10 an improved form of means for attaching the receptacle to wall brackets such as are used on railway cars for supporting card tables, and which is characterized by its adaptability to securely attach the receptacle to various types of wall brackets.

I will describe only one form of safety deposit device embodying my invention and will then point out the novel features in claims.

20 In the accompanying drawings:

Fig. 1 is a view showing in front elevation one form of safety device receptacle embodying my invention in applied position to one form of wall bracket with the closure member of the receptacle removed;

25 Fig. 2 is a vertical sectional view of the receptacle and wall bracket shown in Fig. 1 with the closure member in applied position to the receptacle;

30 Fig. 3 is a fragmentary view showing in front elevation the handle for the closure member;

35 Fig. 4 is a detail perspective view of the stationary attaching arm embodied in the receptacle shown in Figs. 1 and 2;

Fig. 5 is a detail perspective view of the movable attaching arm shown in Figs. 1 and 2; and

40 Fig. 6 is a detail perspective view of the wall bracket shown in Fig. 2.

Similar reference characters refer to similar parts in each of the several views.

Referring specifically to the drawings, my invention in its present embodiment comprises a box B formed of metal or any other suitable material with one side thereof open but adapted to be closed by a closure member C. The rear or opposite side of the box is provided with a slot or opening 15 having an end extension 15^a shown in dotted lines in Fig. 1, and through this slot attaching means is adapted to be extended by which the box is capable of being attached to any one of a plurality of different forms

of wall brackets, such as are used in Pullman cars for attaching card tables to a wall of the car. The attaching means comprises a stationary attaching arm shown in detail in Fig. 4 as constructed from a plate of metal having an elongated portion 16, and a main body portion 17, both of which are riveted or otherwise secured to the inner sides of the box at a point above the slot 15 as shown in Fig. 2. The body portion 17 is curved so as to extend outwardly and upwardly in the form of a hook through the slot 15 at the upper edge of the latter, and the free horizontal edge of the curved body is recessed as indicated at 18. The construction of this attaching arm is such that it is adaptable 55 to many types of wall brackets, the recess 18 accommodating a projection on the wall bracket in a manner to permit the application of the arm to the bracket as will be described more fully hereinafter.

The attaching means also includes a movable arm which, as shown in detail in Fig. 5, comprises a U-shaped head 19, the free ends of the parallel portions of which are provided with their reduced and bent extensions constituting hooks 20 which, in the applied position of the arm as shown in Fig. 2, are adapted to extend through the slot 15 for engagement with a wall bracket. The lower edge of the head 19 is lipped as indicated at 21 in order that the head as a whole may be properly spaced from the back wall of the box. Extending downwardly from this edge is a flat shank 22 provided with a slot 23. The shank is adapted to slide 65 within a recess or depressed portion 24 in the back wall of the box as shown in Figs. 1 and 2, and a screw-threaded stud 25 secured within the back box wall extends through the slot 23 and has thereon a nut 26 which is adapted to be manually rotated by means of a pivoted handle 27 to clamp the shank against movement. The head 19 can be moved vertically to adjust the position of the hooks 20 within the slot 15, and to facilitate manipulation of the horizontal portion of the head between the vertical portions is provided with an upwardly extending lip 28 exposed to the inner side of the box so that it can be readily gripped.

The outer face of the nut 26 is provided with an annular bead 26^a (Fig. 1) recessed at 70 diametrically opposed points as indicated at 75 80 85 90 95 100 105

26^b for the reception of the ends of a locking pin 29 which is adapted to be extended through an opening 25^a in a stud. The pin is provided for the purpose of locking the 5 nut in clamping position with respect to the shank 22 so as to preclude loosening of the nut and a consequent releasing of the attaching arm in respect to a wall bracket and the subsequent removal of the box from the 10 bracket.

The closure member C is removably fitted within the open side of the box and is adapted to be locked in closed position by a suitable lock contained in a closure K. To facilitate handling of the closure member a handle 30 is provided with a right-angle extension 31 pivoted within suitable ears 32 at the inner side of the closure member, such extension projecting through an opening in 15 the cover member as shown in Fig. 2. The outer side of the closure member is recessed as indicated at 34 to receive the end of the finger in a manner to permit it to be extended beneath the handle 30 and to thereby 20 move the handle outwardly to a horizontal position in removing the closure member from the box.

In the present instance I have shown in 30 Figs. 1, 2, and 6 a typical form of wall bracket, and as shown in detail in Fig. 6, this bracket is provided with a slot 35, the upper edge of which is formed with a depending extension 36 designed for the purpose of coacting with a table bracket for 35 securing the latter to the wall bracket. The wall bracket is shown in Figs. 1 and 2 as applied to a wall, and in practice the box may be secured to the wall bracket by first removing the closure member C to gain access to the nut 26. Assuming that the pin 29 is removed from the nut and stud, by 40 means of the handle 27, the nut can be rotated to release the shank 22 thereby permitting vertical adjustment of the head 19. 45 In actual practice the head 19 is adjusted upwardly until the parallel portions are in overlapped relation to the body portion 17 of the stationary arm, thus bringing the two attaching arms in such close relation as 50 to permit both of them being extended into the slot 35 of the wall bracket. With the members 17 extended into the slot, the box is moved upwardly until such member abuts the upper edge of the slot 35 when, by adjusting the movable attaching arm downwardly until the hook members 20 engage the lower edge of the slot 35, the box may 55 be attached to the bracket. By manipulating the nut 26 to securely clamp the shank 22 against vertical movement, the movable attaching arm can be locked in bracket-engaging position thereby locking the box as a 60 unit to the wall bracket.

If it is desired, the pin 29 can now be 65 extended through the stud and into the re-

cesses of the nut for securing the nut in clamping position. By now applying the closure member and locking it in closed position, the nut is no longer accessible to release the movable attaching arm from the wall bracket and consequently the receptacle cannot be removed from the wall bracket except by removal of the closure member. 70

Although I have herein shown and described only one form of safety deposit device embodying my invention, it is to be understood that various changes and modifications may be made herein without departing from the spirit of the invention and the spirit and scope of the appended claims. 75 80

I claim:

1. A safety deposit receptacle comprising a box, one side of which is provided with an opening and the other side of which is open, a stationary attaching arm secured to the box and extending upwardly through said opening, a movable attaching arm adjustable vertically within the box and having a portion extending downwardly through said opening to coact with the stationary attaching arm to secure the box to a wall bracket, means for securing the movable attaching arm in adjusted position, said means being operable from the inner side of the box, a closure for the box, and locking means for 95 the closure. 90

2. A safety deposit receptacle comprising a box having a slot in one side thereof and the other side open, a stationary attaching arm projecting through said slot and adapted to extend into the slot of a wall bracket so as to engage the upper horizontal edge of the latter, a movable attaching arm adjustable on the box and extending through said slot to engage the lower edge of the 100 slot of a wall bracket, and means operable from a point interiorly of the box for securing the movable attaching arm in edge engaging position. 105

3. A safety deposit receptacle comprising a box, one side of which is open and the other side provided with a slot, a stationary arm fixed to the box and projecting through said slot, a movable arm comprising a head of U form having hooked extensions on the 110 parallel portions thereof projecting through said slot, an operating extension on the head between the parallel portions, a slotted shank depending from the head, a stud secured within the box and projecting through said slot, and a nut threaded on the stud to engage the shank and secure the latter in vertically adjusted position. 115 120

4. A safety deposit receptacle as embodied in claim 3 wherein one wall of the box is recessed to receive said shank and guide the latter in its vertical movements. 125

5. A safety deposit receptacle, an attaching arm having a U-shaped head, the free ends of the parallel portions of which are 130

provided with hooked extensions, an operating lip between the parallel portions, and a slotted shank extending from the head.

6. A safety deposit receptacle comprising
5 a box having a slot in one side thereof, a stationary attaching arm having an upwardly hooked portion extending through said slot, a movable attaching arm having downwardly hooked portions extending
10 through said slot, and means for adjusting the movable attaching arm for causing the hooked portions thereof to engage the lower edge of the slot of a wall bracket and to force the hooked portion of the stationary

attaching arm against the upper edge of the 15 slot of the wall bracket thereby securing the box to the bracket.

7. A safety deposit receptacle as embodied in claim 6 wherein the hooked portions of the movable attaching arm are spaced apart 20 to accommodate the stationary attaching arm between to allow an intimate positioning of the arms for the purpose described.

Signed at Los Angeles, in the county of Los Angeles and State of California, this 25 29th day of March, A. D. 1928.

EDWARD S. PEER.
